UNITED STATES PATENT OFFICE.

ALBERT W. GRIFFITH, OF ALLEGHENY, PENNSYLVANIA.

HAT-PIN.

SPECIFICATION forming part of Letters Patent No. 781,419, dated January 31, 1905.

Application filed August 3, 1904. Serial No. 219,812.

To all whom it may concern:

Be it known that I, ALBERT W. GRIFFITH, a citizen of the United States of America, residing at Allegheny, in the county of Allegheny and State of Pennsylvania, have invented 5 certain new and useful Improvements in Hat-Pins, of which the following is a specification, reference being had therein to the accompanying drawings.

10 This invention has relation to certain new and useful improvements in hat-pins, and has for its object the provision of novel means in connection with a pin whereby when the same has been once placed in a hat it will be retained 15 therein until removed.

Another object of this invention is to provide a hat-pin of an extremely simple construction, one which will be strong and durable and highly efficient when used.

20 Briefly described, my improved hat-pin consists of a shank portion having a pointed end and a head secured upon its other end, this head being ornamented as may be desired. Near the head of the pin I make the shank portion 25 of a spiral form, said spiral being composed of a plurality of convolutions of a volute form and tapering inwardly from the center toward both ends, whereby when the pin has been secured within a hat and rotated the 30 same will become fastened therein and will not become loose from the hat or drop therefrom.

The above construction will be hereinafter more fully described and specifically pointed out in the claims, and referring to the drawings accompanying this application like numerals of reference indicate similar parts throughout the several views, in which—

Figure 1 is a perspective view of my improved hat-pin. Fig. 2 is a fragmentary side 40 elevation view of the spiral portion of the pin, and Fig. 3 is an end view of the same.

To put my invention into practice, I have constructed a portion of the pin upon the principle of a screw. It is a well-known fact that 45 hat-pins commonly used often become lost and drop from the hat of the wearer and often inconvenience the person wearing the hat by the trouble of retaining the same upon their head.

I have constructed my improved hat-pin whereby when the same has been once placed 50 in the hat it will be impossible for the same to become lost or loose from the hat until it is removed by the wearer of the hat.

My improved hat-pin consists of a shank portion 1, the one end of which is pointed, as 55 indicated at 2, while upon the other end is placed a head 3, which may be artistically ornamented in any desired manner. My invention resides in providing a spiral 4 near the head of the pin, this spiral being composed of 60 a plurality of convolutions of a volute form and tapering inwardly from the center toward both ends. The spiral 4 is larger at the middle than at either end—that is, the convolutions 77 of the spiral are of a less diameter than 65 the convolution 8, as clearly illustrated in Fig. 2 of the drawings. By forming the convolutions 77 of a smaller diameter than the convolution 8 the spiral may be easily and quickly engaged in a hat, the double-tapered volute 70 form causing the pin when rotated to travel within the hat, and the first rotation of the pin in either placing the same in the hat or removing it will cause the large convolution to engage the hat when placing the pin therein 75 and when withdrawing it will cause the spiral to be removed from engagement with the hat, so that the pin may be readily withdrawn therefrom. My invention resides in this particular form of spiral, and I do not care to 80 limit myself to the shank portion of the pin or the head thereof, but may construct these in the ordinary manner and use any desired ornamentation in connection with the head to enhance the general appearance of the pin. 85

Having fully described my invention, what I claim, and desire to secure by Letters Patent, is—

1. The combination with a pin having a head upon its one end, of a spiral formed integral 90 with said pin, said spiral being composed of a plurality of convolutions of a volute form and tapering inwardly from the center toward both ends, substantially as described.

2. The combination with a pin having a head 95 upon its one end, of a spiral formed integral

with said pin near its head, said spiral comprising a plurality of convolutions, the convolutions at the center of the spiral being larger than the convolutions at each end of the 5 same, the one shank portion of said pin lying in longitudinal alinement with the other, substantially as described.

In testimony whereof I affix my signature in the presence of two witnesses.

ALBERT W. GRIFFITH.
